UNITED STATES PATENT OFFICE

PAUL F. COX, OF CHICAGO, ILLINOIS, ASSIGNOR TO THE GOSS PRINTING PRESS COMPANY, OF CHICAGO, ILLINOIS, A CORPORATION OF ILLINOIS

MULTICOLOR ATTACHMENT FOR FLAT-BED WEB-PRINTING PRESSES

Application filed July 13, 1929. Serial No. 378,166.

This invention relates to web printing presses of that type in which the web is printed by means of upper and lower cylinders respectively cooperating with upper and lower type beds; the web being usually led first between the lower bed and cylinder and then between the upper bed and cylinder to be perfected thereby.

In some of these presses the web is printed only on one stroke of the cylinders while in others the web is printed on both strokes of the cylinders, both types of presses being well-known.

The object of the present invention is to provide a simple attachment for such presses whereby, if desired, a narrow web may be printed on one side by one bed and cylinder and then turned intermediate the beds so that the same side of the web can be thereafter printed in color by the other bed and cylinder.

The invention includes an attachment having angle bars and deflecting rollers whereby a narrow web after being printed on one bed on one side is laterally diverted so that the same side of the web is again printed on the other bed in another color. For example a half width web is led from the lower impression cylinder up over angle bars and rollers and passed to the upper bed at the opposite side of the press. This permits printing both in black and in one color on the same side of the web. A half width web or a quarter width web can be run with this arrangement.

The invention also includes means whereby the rollers can be driven by a small auxiliary motor in the direction of movement of the web at a speed somewhat over the maximum web speed; which motor can be connected to any ordinary lamp socket, or other convenient source of electrical energy.

I will explain the invention with reference to the accompanying drawings which illustrate so much of a flat bed web perfecting press as will enable the invention to be clearly understood; and summarize in the claims the essentials of the invention, and the novel features of construction, and novel

combinations of parts, for which protection is desired.

In the drawings

Figure 1 is a top plan view of part of a flat bed web printing press of the type mentioned, with my novel attachment applied thereto to enable a narrow web to be printed in multi-color. 55

Figure 2 is an end elevation of Figure 1.

Figure 3 is a side elevation of Figure 1. 60

Figure 4 is a detail.

Fig. 5 is a perspective view showing the path of the web through the deflecting devices.

In the drawings 1 and 1a designate type 65 beds and 2 and 2a impression cylinders cooperating with said beds. The web W is ordinarily led first between the lower bed and cylinder to be printed on one side; and then led up over guides 3 and 3a to and between the upper bed and cylinder to be perfected thereby. These parts and their operation being well known, no further description or detailed illustration thereof is necessary. 79 75

In such presses, as ordinarily constructed, the webs can be perfected in one color, but cannot be printed in multi-color. To enable such a press to print a narrow web in multi-color, for instance in black and one other color, I provide at the end of the press adjacent to guides 3, 3a an attachment, comprising a suitable framing, preferably detachably attached to the end of the press frame, and in said framing are mounted an angle bar 4 adjacent the end of the lower bed; an oppositely inclined angle bar 7 adjacent the end of the upper bed; also a guide roller 5 adjacent the outer end of the angle bar 4, and a guide roller 6 adjacent the outer end of angle bar 7. The rollers 5 and 6 are arranged parallel with each other and with the longitudinal axis of the press. 85 90

As shown the outer ends of angle bars 4 and 7 and rollers 5 and 6 are supported in post or standard 8. The rear or inner end of angle bar 4 is connected to a standard 9, and the inner end of angle bar 7 is connected to a standard 9a. The inner end of the roller 6 is supported on a transverse member 10 100

connecting standards 9, 9a and the inner end of roller 5 is supported on a transverse member 10a connecting the standards 9, 9a. These members properly space the standards apart the width of the press frame. The standard 8 may be connected to the standards 9, 9a respectively by braces 11 and 11a as shown in the drawing.

The specific construction of the framing in which the angle bars 4 and 7 and rollers 5 and 6 are mounted is not an essential feature of the invention. The standards 9 and 9a may be provided with arms 9b, 9c, which can be bolted directly to the adjacent ends of the main side frame F of the press, as indicated in the drawings at 9e to hold the attachment securely to the press and space it the proper distance from the press so that there will be an even number of sheet lengths between the upper and lower beds to insure proper register of successive imprints.

The usual adjustable guide roller 2e adjacent cylinder 2a can be used to compensate for any small variation in the sheet lengths and insure register of successive impressions on the web. The braces and bars connecting the standards make the framing rigid, and the whole attachment can be detachably attached to the press by bolts 9e as indicated in the drawings.

The angle bars and rollers of the attachment are so disposed that a narrow web W after being printed on lower bed 1, may be led past the lower guide roller 3 to and over the angle bar 4 by which it is turned at right angles and directed to the roller 5; from roller 5 the web is led to and over roller 6, and thence to and over angle bar 7, by which it is turned at right angles and directed to guide 3a, and thence to and between the upper bed and cylinder to be printed the second time on the same side. The length of the web overlying the upper bed is parallel with the length of web overlying the lower bed but such lengths are at opposite sides of the press.

The drag or friction of the web on the angle bars 4 and 7 and rollers 5 and 6 would create so much resistance to movement of the web that the usual web delivery devices would not be able to properly shift the web forward over the beds in the intervals between impressions (as is required in the operation of such presses) therefore I provide means for driving the rollers 5 and 6 so as to help feed the web and compensate for the additional friction placed thereon in passing over the angle bars 4 and 7.

For this purpose a small electric motor M is placed on a shelf 8a supported by standard 8; motor M is belted by belt 5e to a pulley 5a on roller 5 and turns it in the direction indicated by the arrows in Figure 2. Cross belt 6e drives a pulley 6a on roller 6 from a

pulley 5a on roller 5. These two rollers 5 and 6 are driven by the motor in the direction of travel of the web at a speed somewhat over the desired web speed. The motor M can be attached to any ordinary lamp socket or source of electricity, as indicated in the drawing.

These independently driven rollers 5 and 6 keep the slack out of the loops and turns of the web in the attachment and between the beds 1 and 1a, and assist the usual press web delivery devices in drawing the web through such loops and turns. Without these driven rollers the slack necessary to maintain in the loops would permit the paper to slip on the angle bars 4 and 7 and it would not be possible to properly control it. The independently driven rollers overcome these difficulties and permit the successful turning of the web intermediate the beds.

The whole arrangement or attachment can be placed at the outer end of the press and fixedly or detachably secured to the press frame; and in the latter case the whole attachment can be removed when it is not desired to use same.

I claim:

1. In combination with a flat bed travelling cylinder web printing press having guides for directing a web successively between the cylinders and beds; web deflecting devices at the end of the press adjacent the beds, said devices including upper and lower angle bars and intermediate guide rollers whereby a narrow web after being printed on one bed can be deflected to one side before it reaches the second bed in such manner that the lengths of web over the beds will be parallel but at opposite sides of the press and the same side of the web will be presented to both beds.

2. In mechanism as set forth in claim 1, said web deflecting devices including means whereby the web will be forwarded.

3. In mechanism as set forth in claim 1 said deflecting means including a small electric motor whereby the said intermediate guide rollers may be positively rotated in a direction to forward the web passing thereover.

4. In combination with a flat bed web printing press having upper and lower beds, cylinders cooperating therewith, and means for directing a web successively between the beds and cylinders; inclined angle bars adjacent the outer ends of the beds, and auxiliary guide rollers parallel with the longitudinal axis of the press and arranged intermediate the angle bars whereby a narrow web after being printed on one bed can be deflected to one side before it reaches the second bed in such a manner that the lengths of web over the beds will be parallel but on opposite sides of the press and the same side of the web will be presented to both beds.

5. In mechanism as set forth in claim 4 means whereby the said intermediate guide rollers are rotated in a direction to forward the web passing thereover.
- 5 6. In mechanism as set forth in claim 4 said deflecting means including a small electric motor whereby the said intermediate guide rollers may be positively rotated in a direction to forward the web passing thereover.
- 10 7. An attachment for flat bed web printing presses having upper and lower beds, cylinders cooperating therewith and means for directing the web successively between the beds and cylinders; said attachment comprising a frame attachable to the end of the press, oppositely inclined angle bars mounted in said frame respectively adjacent the ends of the beds; and guide rollers mounted 15 in said frame parallel with the longitudinal axis of the press and intermediate said angle bars; whereby a narrow web after being printed on one bed can be deflected to one side before it reaches the second bed in 20 such a manner that the lengths of web over the beds will be parallel but at opposite sides of the press, and the same side of the web be 25 presented to both beds.
8. In mechanism as set forth in claim 7 means whereby the said intermediate guide rollers are rotated in a direction to forward the web passing thereover.
9. In mechanism as set forth in claim 7 said deflecting means including a small electric motor whereby the said intermediate guide rollers may be positively rotated in a direction to forward the web passing thereover.
- 40 10. In a flat bed travelling cylinder web printing press having superposed beds, cylinders coating with such beds, and guides for directing a web successively between the cylinders and beds, web deflecting devices at the end of the press adjacent the outer ends 45 of the beds, whereby a narrow web after being printed on one bed by one cylinder can be deflected to one side before it reaches the other bed in such manner that the same side of the web will be printed by the other bed and cylinder, and the lengths of web on the beds will be parallel but at opposite sides of 50 the press.
- 55 11. In mechanism as set forth in claim 10, said web deflecting devices including means whereby the web will be forwarded.

PAUL F. COX.
